UNITED STATES PATENT OFFICE

2,669,113

KEY HOLDER

Roswell S. Gillette, Erie, Pa.

Application September 15, 1951, Serial No. 246,811

4 Claims. (Cl. 70—456)

1

This invention relates to key holders and in particular to an improved pocket key case wherein any key can be moved to an "in use" position or removed from the case and wherein all unused keys may lie within the case in flat parallel planes.

Key holders present the particularly unique problem of attempting to provide a secure, flat container for a plurality of keys. Key chains and key rings which have been known and used for years present bulky, cumbersome structures that tend to tear pockets and that are uncomfortable to carry.

An improvement over these key rings and chains is a key case built in the form of a leather or plastic container surrounding a key-holding mechanism; but even key cases as now known leave something to be desired. For example, conventional key cases have a plurality of individual key-holding loops plus a supporting structure. The loops generally are either removable, one or more at a time, out of the case for use, or they are the non-removable type which generally are rotatable to an "in use" position. Key loops of the non-removable type unfortunately are apt to be pulled out from their supporting structure or opened to the extent that keys may become dislodged and be lost. Key loops of the removable type, on the other hand, are usually not easily removed or replaced, and in either the removable or non-removable type, the keys (in storage) do not lie in neat, flat parallel planes for the convenient removal of the underneath keys; and furthermore, all the keys tend to become entangled with each other.

It is an object of this invention, therefore, to provide an improved key case wherein keys are supported in such a manner that they will lie in flat parallel planes against a base when they are in other than the "in use" position.

It is a further object of this invention to provide an improved key case wherein a plurality of keys may be supported in the flat co-planar storage position in a manner that affords convenient access to any key that is to be used or removed from the holder.

It is a still further object of this invention to provide an improved key-holding mechanism formed from a single loop which is adapted for use with a key case and on which any key may be readily moved to the "in use" position or from which any key may be removed from the holder.

It is a still further object of this invention to provide an improved key-holding mechanism which, while providing for the ready installation

2

of keys, insures against their being removed accidentally.

Further objects and advantages of this invention will become apparent and the invention will be more clearly understood from the following description referring to the accompanying drawing, and the features of novelty which characterize this invention will be pointed out with particularity in the claims annexed to and forming a part of this specification.

Briefly, this invention relates to a key-holding mechanism comprising a single loop having a mounting portion, key-holding portions extending upwardly from said mounting portion, and a key "in use" portion spaced from and overlying said mounting portion and extending generally perpendicularly from the outer ends of said key-holding portions. The key "in use" portion is split to provide for the placement of keys on and removal of keys from the loop.

In the drawing, Fig. 1 is a perspective view of a closed key case; Fig. 2 is a perspective view of one modification of my key case; Fig. 3 is a front elevation of an embodiment of my invention having a portion of a locking sleeve shown in section; while Figs. 4 and 5 are front elevations of another embodiment of my improved key case.

While this invention will be described with respect to the limited number of embodiments shown in the drawing, it is to be pointed out that these embodiments have been chosen merely as examples to illustrate more clearly the operating features and principles of this invention.

In the drawing, a key case 1 is shown as comprising a cover 2 and a key-supporting mechanism 3.

Cover 2, which is ancillary to my invention, can be made of any of the conventional materials heretofore used in the art; that is, it can be made of a flat piece of leather or plastic having dimensions making it suitable for overlap to a butting position; or it can be provided with a zipper which will join matching edges of the material to enclose keys and a key-supporting structure.

Key-supporting mechanism 3 in the embodiment shown in Fig. 2 comprises a base 4, a securing device 5, and a key loop 6.

Base 4, preferably, is a plate of metal or any suitable molded plastic which is adapted to lie in a single plane. Since base 4 serves the primary function of providing a stiff backing member, its thickness, width, and length are dependent primarily upon the type and size of the key case desired.

Securing device 5, which is employed to fasten

key loop 6 to base 4, may have various forms. In the embodiment shown in Fig. 2, for example, the securing device 5 comprises a plate 7 having three integral ears 8, 9 and 10. The ears are rolled-over portions of key loop 6, thereby fastening it to plate 7.

Obviously, plate 7, which is not a necessary element, can be secured by conventional means, such as by rivets 11, to base 4 and cover 2.

My improved key loop 6 comprises a mounting portion 12, key-holding members 13, 14 and the key "in use" portion 15. In a preferred embodiment, loop 6 is made from a single strand of a wire having high tensile and resilient properties.

In one form (Fig. 2), mounting portion 12 is an inverted U-shaped section having a base 16 and a pair of legs 17, 18. Mounting portion 12, which is shaped to lie in a plane parallel to base 4, is so constructed (as shown in Fig. 2) that its legs 17, 18 are held by ears 8, 10 while its base 16 is held by ear 9.

Key-holding members 13, 14 extend laterally away from the mounting portion 12. The length of the key-holding members naturally is dependent upon the type and number of keys to be held by the case. For example, to hold several average sized keys, the length of members 13, 14 should be about three-eighths of an inch, but in any event, their length should be consistent with good design appeal.

The key "in use" portion 15 of the key loop 6 overlies the mounting portion 12, and it may extend generally perpendicularly from the outer ends of key-holding members 13, 14. Preferably, the key "in use" portion 15 is an integral part of the key loop 6, and its outer tip portion is deflected toward base 4 to lend a smooth contour to the key case.

The key "in use" portion 15 illustrated in Fig. 2 is in the shape of an angle having both sides extending, one towards each of the key-holding members 13, 14. One of these sides is cut (bias or otherwise) at a point 19 somewhere between the apex and the key-holding portions 13, 14. The cut is so positioned that the key is not apt to become disengaged from the loop when the key is in the "in use" position, "in storage" position, or when being moved between these positions. With this structure, an intentional effort is required to engage or disengage a key from loop 6, because the free ends of the loop adjacent cut 19 have a natural tendency, due to the resilience of the wire, to stay in alignment.

The further embodiments of my invention shown in Figs. 3 and 4 relate primarily to a tubular sleeve 20 having an outer diameter smaller than the hole in the head of a key. Sleeve 20 is positioned over the free ends of the loop 6' at cut 19', thereby aligning the free ends and holding them against separation through loss of resiliency in the loop material.

In use, the sleeve 20 shown in Figs. 3 and 4 could be moved, for example, along loop 6' in either direction. One free end (preferably the upper one) could then be sprung to permit installations of keys, and sleeve 20 would then be returned to its position shown in Figs. 3 and 4 to relock the free ends. This is an added safety feature and might be valuable in some instances. When the free ends of the loop adjacent cut 19 become separated, the longer or shorter end can be readily bent into position. This might be required about every six months, depending on the quality of material in loop 6' and the frequency of adding and removing keys.

In addition to the sleeve 20, Figs. 3 and 4 show other means for securing loop 6' to the case 2'. In each of these figures, a base plate 4 is not employed, but loop 6' is provided with formed eyelets 21, 21', through which rivets 22 may be passed to lock the loop 6' directly to case 2'. While this embodiment does not provide the sturdy structure of Fig. 2, it is adequate for some uses.

10 This improved key holder has filled a need long existing in the art in that it provides a unique structure enabling keys to lie absolutely flat against the base or each other when not in use, and which allows any one of the keys to be moved to the "in use" position or removed from the holder for use. This is done by moving all keys in front of the wanted key to the other storage leg 13 or 14 or on the loop past the cut 19 and "in use" position, thus giving the wanted key access to the cut 19 or "in use" position. This requires less effort than untangling the keys on separate loops in the present types of key holders.

15 In the embodiment of my invention shown in Fig. 5, loop 6'' is shown having two key-holding positions with the cut 19'' depressed between them so that when either position is used the weight of the holder will tend to close the cut 19'' rather than open it.

20 Modifications of this invention will occur to those skilled in the art, and it is desired to be understood, therefore, that this invention is not intended to be limited to the particular embodiments disclosed, but rather it is intended to cover all modifications which are within the true spirit and scope of this invention.

25 What I claim as new and desire to secure by Letters Patent of the United States is:

30 1. A key loop for a key case comprising a resilient wire shaped integrally to form an elongated mounting portion, key-holding portions extending laterally from either end of said mounting portion in substantially parallel side-by-side alignment, and a key "in use" portion spaced from and overlying said mounting portion and joining the outer ends of said key-holding portions, said key "in use" portion having a cut at one point therein whereby adjacent sides of said cut may be separated to provide for the installation and removal of keys from said loop.

35 2. A key loop and mounting plate combination for use in a key case comprising a flat mounting plate having a pair of resilient wires extending laterally therefrom in side-by-side relationship to provide key-holding portions whereby keys may be supported to lie flat and parallel to said mounting plate, and an integral key "in use" portion overlying said mounting plate and connecting the outer ends of said key-holding portions, said key "in use" portion having a cut therein to provide for the separation of the adjacent sides of said cut in opposition to the resiliency of said wire whereby keys may be installed thereon or removed therefrom.

40 3. A key loop for a key case comprising integrally an elongated mounting portion, key-holding portions extending laterally from opposite ends of said mounting portion in parallel side-by-side alignment to provide key storage supports whereby a key when not being used may lie absolutely flat and parallel to said mounting portion, and a key "in use" portion spaced from and overlying said mounting portion, said key "in use" portion having a pair of legs interconnecting the outer ends of said key-holding portions, and said loop having a cut along its

length to provide for insertion of a key on said loop or easy removal of any key therefrom.

4. A key-supporting device comprising a flat mounting plate, a key loop, and means securing said loop to said plate, said loop defining a mounting portion lying in one plane, key-holding portions extending laterally one from each end of said mounting portion in side-by-side alignment, and a key "in use" portion interconnecting the outer ends of said key-holding portions, said 10 loop having a cut in a portion thereof to provide for the installation and removal of keys from said loop.
